UNITED STATES PATENT OFFICE.

CHARLES SPIRO, OF NEW YORK, N. Y.

RIBBON-SHIFTING MECHANISM.

No. 896,866.

Specification of Letters Patent.

Patented Aug. 25, 1908.

Application filed April 27, 1908. Serial No. 429,459.

To all whom it may concern:

Be it known that I, CHARLES SPIRO, citizen of the United States, residing at New York, county of New York, and State of New York, have invented certain new and useful Improvements in Ribbon-Shifting Mechanism, of which the following is a specification, reference being had therein to the accompanying drawing.

10 This invention relates to a ribbon shifting mechanism, and particularly to means for varying the extent of ribbon shift for use in connection with polychrome or multicolor ribbons so as to present either color thereof 15 in the path of the type bar.

The invention has for an object to provide a novel and improved construction whereby the universal bail may be shifted in position relative to the actuating key levers so as to 20 vary the extent of depression necessary to operate this bail and the ribbon shifting arm carried thereby.

A further object of the invention is to provide upon the bail a plurality of adjustable stops adapted to coöperate with the shifting plate carried upon the ribbon arm by which the relative position of said arm to the bail may be varied for the purpose of imparting thereto a greater or less travel, 30 such means being controlled from a position adjacent to the keyboard of the machine.

Another object of the invention is to provide means for feeding the ribbon from the faces of the spool next the typewriter platen 35 so as to provide for the necessary slack required in the shifting of the arm for different lengths of travel relative to the fixed spool.

Other and further objects and advantages of the invention will be hereinafter fully set 40 forth and the novel features thereof defined by the appended claims.

In the drawing:—Figure 1 is a central vertical section showing portions of a typewriter to which the invention is applied; Fig. 2 is a bottom plan of the shifting connection with the universal bail; Fig. 3 is a rear elevation thereof; Fig. 4 is a detail perspective of this connection; Fig. 5 is a similar view of the rod carrying the shifting arms; Fig. 6 is a perspective of the movable plate carried by said arm to engage the stop on the universal bail. Fig. 7 is a detail section on the line 7—7, Fig. 4 of the means for holding the rod, Fig. 8 is a detail perspective of the controlling 55 lever for shifting the mechanism. Fig. 9 is a plan of the ribbon carrier. Fig. 10 is a

diagram showing the path of the type relative to the ribbon under different adjustments of the vibrator.

Like numerals refer to like parts in the several views of the drawing.

Referring to the drawing, 10 designates the frame of a typewriter which may be of any desired construction or configuration, in which the key levers 11 are pivotally mounted at 12 and held in elevated position by means of springs 13. These levers control the type bars in the usual manner. Beneath the levers 11 and pivotally mounted in the frame is a rock shaft 14, Fig. 2, having lever arms 15 to which the universal bail 16 is secured, which bail is normally held in contact with the levers 11 by means of the tension spring 17 extending therefrom to a fixed point. This bail is provided with the usual arm 18 carrying the dog mechanism for the carriage by which the travel thereof is controlled. The bail is provided with the adjustable screws 19 and 20, the heads of which are disposed at different distances from the inner face of the bail so as to control the adjustment of the bail relative to the remaining parts. While headed screws 19 and 20 have been here shown, any other desired projection located at different distances from the bail may be used as equivalent thereof in securing the relative adjustment of the bail to the remaining parts.

For the purpose of shifting the bail by means of the projection thereon, the rock shaft is provided with bearings 21 in which the sliding rod 22 is mounted, this rod having secured thereto the ribbon shifting arms 23 adapted to receive a polychrome or other ribbon 24 fed from the spools 25 in the usual manner, and passing over the carrier 26 carried at the upper end of these arms, for instance, as shown in my prior patent No. 475,623, May 24, 1892. These arms engage a fixed abutment 55 having an adjusting screw 56 therein to limit the travel of the arms in one direction. Other means may be used for forming a stop for the arms or moving parts by which they are carried.

For the purpose of providing for the necessary slack in the ribbon incident to the shifting of the ribbon carrying arms for different degrees of travel the ribbon is fed from the side of the spool next the platen, as shown at 27, and at the opposite side of the spool from the tension arm 28, it being understood that this spool is intermittently operated in the

movement of the arms 23, as usual in the art. The rod 22 is adapted to be shifted by any desired connection, for instance, the bell crank lever 29 pivotally mounted at 30 upon the frame of the machine, and having the slotted arm 31 embracing the pin or projection 32 from the rod 22. This lever is connected by the link 33 with the operating lever 34 which in the present instance is pivotally mounted at 35 upon one side of the machine frame adjacent to the keyboard thereof. The lever is adapted to coöperate with the indicator plate 36 having designations 37 and 38 thereon to show which section of the ribbon is in use and an indication 39 by which the lever may be positioned so that the ribbon is held out of use as for the purpose of stenciling or mimeograph work. The rod may be frictionally held in its several adjusted positions by any desired means, for instance, a series of grooves 40 therein adapted to coöperate with a spring pressed pin 41 mounted in an aperture 42 in one of the bearings 21. The resistance is sufficient to hold the rod in its several positions. This rod has also mounted thereon an adjusting plate 43 provided with elongated apertures 44 in which the projecting lugs 45 from the ribbon arms 23 are disposed. This plate is secured in position by the curved end portions 46 thereof through which screws 47 or other attaching devices may extend, and from one end of these lugs the operating plate 48 is projected from the rod and provided with contact faces 49 and 50 adapted to move beneath the heads of the projections 19 and 20 carried by the universal bail. For the purpose of securing rigidity in the contact of the plate 48 with these projections, the free end thereof is bent to form lugs 51 and 53 each disposed in a different plane and having an inclined edge to ride upon the raised surface 54 carried by the bail and thus force the faces 49 and 50 into contact with the projections. When screws are used for the purpose of these projections they may be secured in their adjusted position by set screw 52 mounted in the bail to engage the stem of the screws.

Fig. 10 diagrammatically illustrates the path of the type upon the ribbon 24. When adjusted for the shortest extent of vibration of the ribbon arm the type impression is upon the portion 60, and when adjusted for the longest vibration is upon the portion 61 of the ribbon. By an intermediate adjustment of the arm relative to the bail the ribbon is not moved into the path of the type and therefore no impression is made thereon as when mimeographing.

In the operation of the invention it will be seen that the plate 46 can only move downward with the bail and its upward travel beyond the normal position is prevented by the abutment engaging the arms so that when

shifted into contact with the parts carried by the bail the latter is moved relative to the plate to vary its length of travel. When the face 49 on the operating plate is adjusted beneath the projection 19 from the bail the movement thereof is limited and the ribbon arm shifted for its shortest length of travel as in the use of black or the principal color used. If it be desired to use red or a contrasting color a shifting of the keyboard lever moves the rod carrying the operating plate into the position shown in Fig. 4 where the face 50 thereof extends beneath the longer projection from the bail thus allowing a greater degree of depression and a consequent longer travel of the shifting arm to bring into the path of the typebar the portion of the ribbon carrying the contrasting color. In this movement the holding lug 53 rides upon the projection 54 of the bail and firmly supports the plate in its adjusted relation. In the opposite travel of this plate the lug 51 rides upon the surface 54. When the lever 34 is located at the indication 39, the plate 48 is disposed between the projections 19 and 20 so that the bail is disconnected from the ribbon shifting arm and no vibration of the ribbon occurs it being held out of the path of the type bar so that the latter may be used for stenciling or other work where no original impression is necessary or desired.

This invention presents a simple, efficient and economically constructed form of ribbon shifting mechanism by which the extent of travel of the ribbon may be controlled by means of the adjustment of the universal bail relative to the ribbon operating plate, and the projections of different lengths carried by this bail may be adjusted to secure the desired vibration of the ribbon. The feeding of this ribbon from the face of the spool next the platen provides for the necessary slack therein incident to the different degrees of vibration of the ribbon carrying arms and prevents the forming of slack at any point which would affect the ribbon feed or the type bar contact with the ribbon.

Having described my invention and set forth its merits, what I claim and desire to secure by Letters Patent is:

1. In a ribbon shifting mechanism, a universal bail, a rock shaft, a ribbon carrying arm supported from said shaft, and shifting means carried by the shaft to contact with and vary the travel of said bail.

2. In a ribbon shifting mechanism, a universal bail, a rock shaft, a ribbon carrying arm supported from said shaft, shifting means carried by the shaft to vary the travel of said bail, and projections of different lengths upon said bail adapted to engage said shifting means.

3. In a ribbon shifting mechanism, a universal bail, a rock shaft, a ribbon carrying

arm supported from said shaft, shifting means carried by the shaft to vary the travel of said bail, and a keyboard lever operably connected to said shifting means.

5 4. In a ribbon shifting mechanism, a universal bail, a rock shaft, a ribbon carrying arm supported from said shaft, shifting means carried by said shaft to vary the travel of said bail, projections of different lengths 10 upon said bail adapted to engage said shifting means, and means for adjusting the length of said projections.

15 5. In a ribbon shifting mechanism, a universal bail, a rock shaft provided with bearings, a sliding member mounted in said bearings, ribbon carrying arms engaging said member, and an operating plate normally held against movement in one direction of the bail travel and projected from said member 20 into the path of said bail to shift and vary the travel thereof.

25 6. In a ribbon shifting mechanism, a universal bail, a rock shaft provided with bearings, a sliding member mounted in said bearings, ribbon carrying arms engaging said member, an operating plate normally held against movement in one direction of the bail travel and projected from said member 30 into the path of said bail said plate having holding surfaces disposed in different planes to shift said bail.

35 7. In a ribbon shifting mechanism, a universal bail, a rock shaft provided with bearings, a sliding member mounted in said bearings, ribbon carrying arms engaging said member, an operating plate normally held against movement in one direction of the bail travel and projected from said member 40 into the path of said bail and having holding surfaces disposed in different planes to shift said bail, and means for retaining said sliding member in shifted position.

45 8. In a ribbon shifting mechanism, a universal bail, a rock shaft provided with bearings, a sliding member mounted in said bearings, ribbon carrying arms engaging said member, an operating plate normally held against movement in one direction of the bail travel and projected from said member 50 into the path of said bail to shift and vary the travel thereof, an operating lever disposed at the keyboard, a link extending rearwardly therefrom, and a crank lever connected to said link and to said sliding member.

55 9. In a ribbon shifting mechanism, a universal bail, a rock shaft provided with bearings, a sliding rod mounted in said bearings, a slotted adjusting plate mounted upon said rod, a ribbon carrying arm mounted upon said rod and provided with projections extending into the slots of said plate, and means extending from said rod to contact with and vary the travel of the universal bail.

60 10. In a ribbon shifting mechanism, a universal bail, a rock shaft provided with bear-

ings, a sliding rod mounted in said bearing, a slotted adjusting plate mounted upon said rod, a ribbon carrying arm mounted upon said rod and provided with projections extending into the slots of said plate, and a deflected operating plate carried by said rod and disposed beneath said universal bail to contact therewith and vary the travel thereof.

70 11. In a ribbon shifting mechanism, a universal bail, a rock shaft provided with bearings, a sliding rod mounted in said bearings, a slotted adjusting plate mounted upon said rod, a ribbon carrying arm mounted upon said rod and provided with projections extending into the slots of said plate, a deflected 75 operating plate carried by said rod and disposed beneath said universal bail, and spaced projections carried by the under face of the universal bail at opposite sides of said operating plate.

80 12. In a ribbon shifting mechanism, a universal bail, a rock shaft provided with bearings, a sliding rod mounted in said bearings, a slotted adjusting plate mounted upon said rod, a ribbon carrying arm mounted upon 85 said rod and provided with projections extending into the slots of said plate, a deflected operating plate carried by said rod and disposed beneath said universal bail, contact faces upon said operating plate and 90 spaced projections of different lengths at opposite sides of said plate in the path of said faces when shifted.

95 13. In a ribbon shifting mechanism, a universal bail, a rock shaft provided with bearings, a rod having peripheral grooves adjacent to one of said bearings, a friction retaining device carried by said bearings, means carried by said rod to shift the universal bail and normally held against movement in one 100 direction of the bail travel, ribbon arms carried by said rod, a pin extended laterally from said rod, a crank shaft having a slotted arm engaging said pin, and means for operating the opposite arm of said shaft.

105 14. In a ribbon shifting mechanism, the combination with a platen, of ribbon spools, a ribbon carrying arm movable toward and from the platen, means for vibrating said arm for different predetermined extents toward and from the platen, and a ribbon fed by said arm from one of said spools at the side next the platen to permit a swinging movement of the ribbon toward and from the spool axis.

110 15. In a ribbon shifting mechanism, a rock shaft, a universal bail carried thereby, a shifting device mounted upon said rock shaft, and an operating plate extending from said device to engage and vary the travel of 115 said bail for different distances.

120 16. In a ribbon shifting mechanism, a rock shaft, a universal bail carried thereby, a shifting device mounted upon said rock shaft, an operating plate having a contact 125

- face with holding lugs disposed in different planes, and headed projections upon the universal bail disposed beneath said faces at opposite sides of said plate.
- 5 17. In a ribbon shifting mechanism, a rock shaft, a universal bail carried thereby, a shifting device mounted upon said rock shaft, an operating plate having a contact face with holding lugs disposed in different planes, 10 headed projections upon the universal bail disposed beneath said faces at opposite sides of said plate, and means for adjusting said projections relative to said bail.
- 15 18. In a ribbon shifting mechanism, a universal bail, a rock shaft, a shifting device carried thereby and provided with an operating plate depending therefrom, and projections of different lengths from said bail spaced at opposite sides of said plate to permit an inactive position of the plate intermediate of 20 said projections.
19. In a ribbon shifting mechanism, a universal bail, a rock shaft, a shifting device carried thereby and provided with an operating 25 plate depending therefrom, projections of different lengths from said bail spaced at opposite sides of said plate to permit an inactive position of the plate intermediate of said 30 projections, a ribbon carrier mounted upon said rock shaft, and a keyboard shifting mechanism adapted to move said operating plate into contact with either projection or intermediate thereof.
20. In a ribbon shifting mechanism, a universal bail provided with spaced projections 35 of different lengths, and a shifting device normally held against movement in one direction of the bail travel and having an oper-
- ating face adapted to contact with either of said projections to shift the bail. 40
21. In a ribbon shifting mechanism, a universal bail, provided with spaced projections of different lengths, a shifting device having an operating face adapted to contact with either of said projections, and a holding device projected from said shifting device to engage a surface of said bail. 45
22. In a ribbon shifting mechanism, a universal bail provided with spaced projections of different lengths, a shifting device having an operating plate adapted to contact with said projections, and holding lugs of different lengths extended from said plate to engage a surface upon said bail. 50
23. In a ribbon shifting mechanism, a universal bail provided with spaced projections of different lengths, a shifting device having an operating plate disposed to engage said projections, holding lugs of different lengths 55 extended from said plate, and a raised surface upon said bail disposed in the path of travel of said lugs. 60
24. In a ribbon shifting mechanism, a shifting device comprising an operating plate having its free end bent upon itself and bifurcated to form parallel laterally extending lugs of different lengths, a bail disposed to engage said lugs, and means for normally holding 65 said device against movement in one direction of the bail travel. 70

In testimony whereof I affix my signature in presence of two witnesses.

CHARLES SPIRO.
